UNITED STATES PATENT OFFICE.

LOUIS OESTERLE, OF CHICAGO, ILLINOIS.

WIND-INSTRUMENT.

SPECIFICATION forming part of Letters Patent No. 329,940, dated November 10, 1885.

Application filed April 13, 1885. Serial No. 162,011. (No model.)

To all whom it may concern:

Be it known that I, LOUIS OESTERLE, a citizen of the United States of America, residing at Chicago, in the county of Cook and State of Illinois, have invented certain new and useful Improvements in Wind-Instruments, of which the following is a specification, reference being had therein to the accompanying drawings.

10 My invention relates to certain improvements in wind-instruments.

The object of the invention is to improve the arrangement of means for operating the different keys of the instrument; and to that end it consists of certain novel devices and combination of devices, as will be described and claimed.

Reference will be made to the accompanying drawings, in which Figures 1 and 2 are views, partly in elevation and partly in section, of the keys and their operating mechanism; Figs. 3, 4, 5, and 6, different cross-sections; Fig. 7, a detail view of one style of key; Fig. 8, a detail of part of the operating mechanism; Fig. 9, a view showing certain of the keys and their connections; Fig. 10, a continuation of Fig. 9; Figs. 11, 12, sections of Figs. 9, 10, respectively; and Figs. 13, 14, 15, 16, and 17, details of parts.

30 Like letters refer to like parts in each view.

A represents the instrument to which the improvements are applied.

B represents one of the keys, it being the last key on one side. It is fastened to a sleeve, a, mounted upon a stationary shaft, b.

35 Sleeve a is provided at one end with a crank-arm, c, in which is mounted one end of a shaft, d, said shaft being secured at its opposite end to a crank-arm, e, of a shaft, f, to be referred to.

At the point shown in Fig. 1 there is secured to shaft d a key, C, situated directly above a key, D, with which it is adapted to contact when depressed.

40 Formed upon the side of the shank of key D is a projection, g, carrying a set-screw, h, arranged to contact with an offset, k, when the key is depressed, the offset being formed upon a sleeve, l, securely fastened to a shaft, m.

45 Secured to sleeve l is a key, E, thus arranged to be operated whenever compound key C D is depressed, but which is free to be

operated independently of such compound key.

Secured to shaft f, hereinbefore referred to, 55 is an L-shaped arm, n, in the long arm of which are mounted two set-screws, o p. Screw o is adapted to contact with an offset, q, formed upon one end of a shaft, s, to the opposite end of which a sleeve, t, is secured. Screw p contacts with an offset, v, formed upon one end of a sleeve, w, loosely mounted upon shaft s. A key, F, is secured to sleeve t, and a key, H, to sleeve w.

By the arrangement of parts as thus far described it will be seen that whenever the compound key C D is depressed the key B is operated through the medium of rod d, crank-arm e, and sleeve a; key E is operated through the medium of set-screw h and offset k; key 65 F through the medium of rod d, crank-arm e, shaft f, arm n, set-screw q, shaft s, and sleeve t; and key H is operated through the medium of shaft d, crank-arm e, shaft f, arm n, set-screw p, offset v, and sleeve w, arrangement 70 being thus made for the operation of five keys by the simple depression of one compound key.

As before mentioned, the arrangement of key E with respect to compound key C D is such 80 that it may be operated independently of such compound key.

Formed with the sleeve w are two bearings, x, for a short shaft, y. Keyed upon shaft y is a key, G, the shank of which is provided with 85 a rearward extension, a', suitably curved to partly surround the sleeve w. By this arrangement, should key G be depressed, extension a' will contact with sleeve w, the bearings x forced to describe the arc of a circle, sleeve w partly 90 revolved, and key H operated; but should the pressure be applied to key H there will be sufficient play to the bearings x to allow of such depression without operating key G, the two keys being on different centers.

95 It will be understood that keys G H, when not operated upon, are held elevated by a spring, b'.

The key D, hereinbefore referred to, is secured to a sleeve, c', mounted loosely upon a shaft, m. Formed upon sleeve c' are two 100 bearings, d', for a short shaft, e'. Mounted upon shaft e' is a key, K, and also an arm, f', which is curved to partly surround sleeve c', this arrangement of parts being substantially

- similar to the arrangement described in connection with keys G H, the only difference being that, instead of forming the shank of key K with a rearward extension similar to a' of key G, the arm f' is provided, the result being the same, but this arrangement being desirable in order to shorten elevating-spring g' as much as possible. By this arrangement it will be seen that when key K is depressed key D is operated through the medium above described, and key E through set-screw h and offset k , three keys being thus operated from one, while at the same time key D may be operated independently of key K.
- 15 Key P, to be hereinafter referred to, is operated by the fourth finger, and should it be on the same level as the keys operated by the other fingers of the same hand its operation would be difficult, as the movement of that finger is not free. To obviate this difficulty I mount, upon the upper face of the key K, and a key, L, to be referred to, and between which two keys P is located, a knob, K', provided with a suitable socket, into which a screw, h' , is inserted, as shown in Fig. 7. These knobs are on a slightly higher plane than the key P, and means thus provided for the free working of said key P by the fourth finger.
- 20 L represents one of the keys loosely mounted upon the shaft b , before referred to. Formed upon the shank of key L is an arm, k' , in which is mounted a set-screw, l' . Screw l' is adapted to contact with an offset, m' , formed upon one end of the shaft m , to the opposite end of which sleeve l is secured, the key E being mounted upon said sleeve, as before mentioned. By this arrangement it will be seen that key E may be operated from key L, but 25 at the same time is free to be operated by compound key C D without affecting said key L. Situated directly above key F is a key, M, secured to a shaft, n' , said shaft having bearings at one end in an arm, o' , loosely mounted upon a shaft, p' , upon the opposite end of which a crank-arm, q' , is formed, to which reference will be made. Shaft n' at the point shown is provided with an arm, b^2 , which projects over a key, N, and in which is 30 mounted a set-screw, s' . Key N is fastened to the shaft p' . At its opposite end shaft n' is secured to a crank-arm, t' , formed upon one end of a sleeve, v' , upon the opposite end of which a similar arm, w , is formed.
- 35 55 Mounted in crank-arm w' is a shaft, x' , which at its opposite end is secured to a crank-arm, y' , formed with a sleeve, a^2 , to which a key, O, is secured. By this arrangement, when compound key F M is operated, the key N is operated through the medium of shaft n' , arm b^2 , and set-screw s' , while key O is also operated through the medium of shaft n' , crank-arm t' , sleeve v' , arm w , shaft x' , arm y' , and sleeve a^2 .
- 60 P represents a key secured to a sleeve, c^2 , loosely mounted upon shaft m . Secured to sleeve c^2 is a crank-arm, d^2 , in the opposite end of which a shaft, e^2 , is mounted, said shaft

being secured at its opposite end to the crank-arm q' , before referred to. At that end of shaft e^2 where it has bearing in crank-arm d^2 it is provided with a tapered opening, f^2 , Fig. 8, into which a set-screw, g^2 , is inserted. By this arrangement of parts, when key P is depressed, the key N is operated through the medium of sleeve c^2 , crank-arm d^2 , shaft e^2 , crank-arm q' , and shaft p' ; but when key N is operated shaft e^2 is allowed sufficient play, because of opening f^2 , to avoid operating key P.

Q represents a thumb or first-finger key near the front end of the instrument, secured 80 to a sleeve, h^2 , loosely mounted upon shaft p' , such key being entirely independent.

To provide means for operating key N from the opposite side of the instrument, I provide the shank of such key with a tooth, k^2 , Fig. 3, 85 with which a similar tooth, l^2 , is adapted to contact, the latter being formed upon the shank of a finger-lever, R, mounted upon a short shaft, m^2 . (Shown in Figs. 9, 15.) The key H is provided with a tooth, n^2 , to contact 90 with a tooth, o^2 , formed upon a short shaft, p^2 , and to the opposite end of which a finger-lever, S, is secured.

T V represent two keys, the two first on their side of the instrument. Key T is mounted 95 upon a shaft, q^2 , having bearings in suitable brackets, r^2 , and having at its opposite end an arm, s^2 . Arm s^2 occupies a position directly above an L-shaped arm, t^2 , secured to a shaft, v^2 , said shaft mounted at one end in one of the 100 brackets r^2 . Secured to shaft v^2 about midway its length is a finger-lever, W, by depressing which key T is operated through the medium of shaft v^2 , L-shaped arm t^2 , arm s^2 , and shaft q^2 . Mounted upon shaft q^2 is a sleeve, w^2 , to one end of 105 which is secured key V. Secured to the opposite end of this sleeve is an arm, x^2 , which occupies a position directly above the free end of an L-shaped arm, y^2 , secured to a sleeve, a^3 , mounted upon shaft v^2 , and carrying finger-lever x , the key V being thus operated by sleeve a^3 , arms $y^2 x^2$, and sleeve w^2 .

Finger-lever W was described as situated midway of shaft v^2 , and for convenience in playing I secure to the end of said shaft an additional finger-lever, Y, from which key T may be operated.

To obtain a similar convenience in operating key V, I employ a finger-lever, A', mounted upon a sleeve, b^3 , said sleeve being provided 120 at its opposite end with an L-shaped arm, c^3 , above the free end of which an arm, d^3 , is located, said last-named arm being secured to the sleeve a^3 .

B' B' represent two keys mounted upon independent sleeves $e^3 f^3$, to the latter of which a finger-lever, C', is secured, by which arrangement either key may be operated separately, while at the same time the position of lever C' renders the working of the two at the same 130 time easy.

Formed with offset q , before referred to, but upon the opposite side of the shaft s , is a tooth, g^3 , with which a similar tooth, h^3 , formed with

arm x^2 , is adapted to contact, this arrangement serving to operate key F, whenever key T is operated from its finger-lever. This arrangement is shown in Fig. 6.

5 What I claim is—

1. In a wind-instrument, the combination, with a key thereof, of a second key situated directly over the first and arranged to contact therewith, the two keys moving from the to same center, as set forth.

2. In a wind-instrument, the combination, with a key mounted upon a sleeve, with which are formed suitable bearings, of a second key secured upon a shaft mounted in said bearings, and a curved arm encircling the sleeve, as set forth.

15 3. In a wind-instrument, the combination, with a key thereof, of a shaft provided with a

tapered opening, a set-screw inserted into said opening, a second key, and suitable shafts in- 20 termediate of the keys, as set forth.

4. The combination, with key H, mounted upon sleeve w, said sleeve provided with bearings x, of shaft y and key G, provided with shank a', as set forth.

25 5. The combination, with shaft e², provided with tapered opening f² and set-screw g², of keys N P and intermediate connecting-shafts, as set forth.

In testimony whereof I affix my signature in 30 presence of two witnesses.

LOUIS OESTERLE.
